TENDER STRUCTURE

William A. Newman, Montreal, Quebec, Canada

Application January 16, 1932, Serial No. 587,063

20 Claims. (Cl. 105—234)

This invention relates to railway rolling stock and consists in novel locomotive tender framing arranged for various locomotive auxiliary equipment units, such as the stoker engine, turbo-generator, air and water pumps and air reservoir.

At present it is customary to mount the equipment mentioned on the boiler or on the engine bed either at the front or at the side of or below the boiler. The air and water pumps particularly are comparatively large and heavy units and because of their proximity to other equipment are mounted with some difficulty. The stoker engine is usually located adjacent to the cab deck which location necessitates the extension of the driving connection to the stoker feed screw across the space between the engine and tender and otherwise complicates the coupling of the engine and tender because it restricts the space for the draw bars, piping, and other equipment, and requires a telescoping joint in the driving connection. The engine parts are not readily accessible for inspection and repairs.

In order to avoid some of the above-mentioned difficulties, the mounting of the air and water pumps on the engine front deck has been suggested. However, this necessitates the lengthening of the engine and complicates the proper distribution of weight on the drivers. Obviously, the stoker engine, located beneath the cab, similarly affects the weight distribution.

Moreover, the weight of the large locomotives now being built approaches the maximum permissible rail loads and makes desirable the removal of heavy equipment to the tender.

One object of the present invention is to provide a compressed air reservoir in the tender framing.

Another object of the present invention is to provide tender structure for carrying the air and water pumps, stoker engine, and turbo-generator and, accordingly, decreasing the weight of the engine.

Another object is to facilitate the mounting and dismounting of the above-mentioned equipment and place the same in a position to be more readily accessible for the purpose of inspection and repairs.

Another object is to simplify the connection between the stoker engine and stoker feed screw.

Another object is to provide a suitable passage for piping between the locomotive and the equipment at the rear of the tender.

These and other objects are attained in the structure illustrated in the accompanying drawings in which—

Figure 1 is a top view of the rear end of a tender embodying my invention but with the top plate of the water compartment removed and the vertical plates sectioned.

Figure 2 is a rear view of the same.

Figure 3 is a side view of the novel tender structure with the tank side sheet removed.

Figure 4 is a partial vertical longitudinal section taken substantially on the line 4—4 of Figure 1.

Figure 5 is a vertical transverse section taken on the line 5—5 of Figure 1.

Figure 6 is a similar section taken on the line 6—6 of Figure 1.

Figure 7 is a detail vertical longitudinal section taken on the lines 7—7 of Figures 1 and 5.

Figures 8, 9 and 10 are detail sections taken on the corresponding section lines of Figure 1.

Figure 11 is similar to Figure 1 but illustrates a modified structure and is taken on the line 11—11 of Figure 12.

Figure 12 is a rear view of the same.

Figure 13 corresponds to Figure 7 but illustrates the modification of Figures 11 and 12.

Figures 14 and 15 are detail sections on corresponding section lines of Figure 13.

The tender rear end structure illustrated in Figures 1 to 10 is applied to an integral waterbottom tender underframe casting of the general type disclosed in Patent No. 1,663,036, issued to Pflager & Ashe. The underframe includes side sills 1, rear end sill 2 having the usual draft sills 3 depending therefrom, box-shaped center sill 10, and bottom web 4 which constitutes the tank bottom. A vertical web 9, extending across the underframe on a line spaced from the end sill 2, forms the rear wall for the water space within the underframe casting and also projects slightly above the top of the casting to provide a shoulder S.

Mounted upon the portion of the underframe rearwardly of upright web 9 and abutting shoulder S is an upright box-like skeleton structure comprising an outer frame including transverse horizontal members 11 and 12 and vertical posts 15, 17 and 19, and an inner frame including horizontal members 13, 14, 23, 24, 25 and 26, and vertical posts 16, 18, 20, 21, 22, 27 and 28. These frame portions are connected by upper bars 29, 30, 31, lower bars 32, 33, 34, 39, 40, 41, 42, intermediate side bars 35 and 36, and intermediate center bars 37 and 38.

The various elements of the skeleton frame structure are shaped for maximum strength and convenience of attaching other members thereto,

and preferably, but not necessarily, form an integral structure which may be applied to the tender underframe as a unit.

Preferably, the upper outer portion of the upright frame includes an air reservoir 80 extending from side to side of the tender, the wall of the reservoir merging with the flanges of the transverse member 11.

The tender superstructure includes a top sheet 10 5, end sheet 6, and side sheets 7, all of which may be secured to the tender framing by riveting or welding. A coal hopper having a bottom sheet 8 is provided in the forward portion of the superstructure. An end sheet 6 is spaced inwardly 15 from the rear end sill 2, but the top and side sheets of the tank extend rearwardly substantially to the end of the underframe and form an enclosure for the equipment mounted in the box-like upright frame.

20 Mounted on the right-hand side of the structure (Figures 1 and 2) are a water pump 43, secured to the horizontal and vertical members 25, 26, 27 and 28, and a turbo-generator 44 secured to pads 53 on the horizontal web 54 extending between longitudinal bottom members 41 and 42 and braced by the rib R. (Figure 7.)

On the left-hand side of the structure, air pump 45 is secured to vertical and horizontal members 21, 22, 23 and 24, and stoker engine 46 is secured to pads 55 on longitudinal bottom members 39 and 40.

To provide for the various steam, air, and water connections extending between the engine and the equipment mounted on the rear end of the tender, the upper corners of the superstructure include longitudinal passages 47 and 48 formed by suitable plates connected to the top and side sheets.

40 A cylindrical housing 56 extends from an opening 57 in the tank end sheet 6 through the water space of the tender superstructure to the coal hopper 8. Within this housing extends a driving shaft 59 which has flexible couplings 60 and 61 with stoker engine 46 and feed screw 62 respectively, the feed screw being located in trough 58 in the bottom of the hopper.

Water is led from the tender to the water pump 43 through pipe 63 and then passes through pipe 64, which is enclosed in the passage 48, to 50 a feed water heater. Live steam for operating the air pump 45 and stoker engine 46 is led from the boiler through pipes 65 and 66 enclosed in passage 47 where they extend along the tender. Live steam for the water pump 43 and generator 55 44 reaches the respective units through pipes 68 and 67 in passage 48. Exhaust steam passes from the air pump 45 through pipe 69, from the stoker engine through pipe 70, from the generator through pipe 71 and from the water pump through pipe 72. Pipe 72 is larger in diameter 60 than the other pipes and the other pipes lead into pipe 72 which conducts the total exhaust over the top of the tender superstructure to the tender water compartment.

65 Pipe 81 leads from the air pump 45 upwardly and rearwardly to a coil 82 of radiating pipes from which the air passes through a connection 83 to the reservoir 80 from which air is supplied to the air brakes and other equipment utilizing compressed air.

70 Figures 11 and 12 illustrate a modified structure, the principal differences being that the air reservoir is omitted from the end casting and the piping leads from the equipment mounted on the

rear end of the tender through a passage therefor formed in the underframe.

In this modification the rear upright members 85 and the forward upright members 86, the lower transverse members 87, the upper transverse members 88 and the intermediate transverse members 89 and the longitudinal members 90, connecting the front and rear portions of the frame, are substantially the same as in the structure illustrated in Figures 1 to 10. 10

The water pump 43, turbo-generator 44, the air pump 45 and the stoker engine 46 are mounted on the end frame as previously described, but the piping to and from this equipment is conducted through passages 91 formed in the underframe 15 by the bottom web W and the side wall W' of the latter, and an integral wall 92 and top web 93 cast therewith to form a box-like chamber, the lower wall of which may have openings 111 to provide access to the piping. A section through 20 these housings is indicated in Figure 15.

The water supply pipe 94 comes through the right-hand passage 91 and leads to the water pump 43 and the water is discharged through pipe 95 which leads back to the locomotive through 25 the left-hand passage 91. Live steam for operating the air pump and stoker engine comes through pipes 96 and 97 respectively, located in left-hand passage 91, and live steam for the water pump and generator comes through pipes 20 98 and 99 respectively, located in the right-hand passage 91. Pipe 104 leads from the air pump to the air reservoir.

Exhaust steam from the stoker engine leads 35 through pipe 101 which discharges into pipe 100 leading from the air pump 45. Exhaust steam from the water pump leads through pipe 103 and receives the discharge from pipe 100 and also receives the discharge from the generator leading through pipe 102. Pipe 103 extends over 40 the top of the tank to the locomotive similarly to the arrangement previously described.

The structure in Figures 11 and 12 utilize a lighter end frame member by eliminating the air tank, which arrangement may be preferred if it is 45 satisfactory to mount the air tank on the locomotive. This structure also eliminates the provision of passageways in the upper portion of the tank body, which may be preferred in some installations. 50

It will be understood that the structure of both forms is adapted for or could easily be arranged to mount other equipment advantageously. The underframe need not be of the water-bottom type shown, but could be of any design which is provided with suitable elements for attachment of the rear end structure. The rear end structure need not be integral as shown, as the invention could be embodied in a built-up structure. The various framing members may vary in number, 55 shape and size, according to the requirements of the equipment to be accommodated.

These and other modifications may be made in the structure illustrated without departing from the spirit of the invention and I contemplate the 65 exclusive use of all such modifications as come within the scope of my claims.

What is claimed is—

1. A locomotive tender superstructure framing member comprising an upright box-like frame 70 adapted to be mounted as a unit on the tender underframe and to extend upwardly therefrom and substantially from side to side of the tender and for a relatively short distance longitudinally 75 of the tender and arranged to carry various units

- of locomotive operating equipment a substantial distance above the tender underframe.
2. A locomotive tender superstructure framing member comprising spaced upright frames connected by cross bars, at least one of said frames including transverse brace elements adapted to mount engine equipment.
3. A locomotive tender superstructure framing member comprising forward and rear upright frames connected by cross bars on at least three sides of said member including the lower side thereof, said forward frame including a bracing element adapted to mount engine equipment and at least one of the cross bars on the lower side of said member also including elements for mounting engine equipment.
4. A locomotive tender superstructure framing member comprising horizontally spaced upright frames and connecting elements on all sides and in the middle, at least one of said frames and at least one of said connecting members being adapted to mount engine equipment.
5. An integral tender rear end structure comprising a box-like frame adapted to be mounted on the tender underframe and including elements for mounting engine pumps, a turbo-generator, stoker driving mechanism, and like equipment.
6. An integral tender superstructure member comprising a framework adapted for mounting engine equipment, the sides and top thereof being adapted to mount tank sheets.
7. In a tender underframe, side, center, and rear end sill members, and a transverse member spaced from said end sill member and extending above said side, center, and end sill members, each of said members including elements for attachment of a tender rear-end equipment-mounting structure.
8. In a tender, an underframe, tank and coal hopper superstructure, a fuel feeding device therein, and an upstanding frame member carried by said underframe at the rear of said tank, and a stoker engine mounted on said member.
9. In a tender, an underframe including a rear end portion, and superstructure including a tank, the rear end of said tank being disposed inwardly from the end of said underframe, and the rear end portion of said underframe including elements for mounting engine equipment.
10. In a tender, an underframe including a rear end portion, superstructure including a tank, the rear end of said tank being disposed inwardly from the end of said underframe, and an upright box-like skeleton frame member mounted on said rear end portion and having elements for mounting engine equipment.
11. In a locomotive tender, an upright rear end frame of skeleton box-like structure and an air reservoir extending across said frame from side to side of the tender with the wall of said reservoir merging with the elements of said frame.
12. In a locomotive tender, an upright skeleton box-like rear end frame, an air reservoir carried on the upper portion of said frame and an air pump mounted on said frame below said reservoir and connected therewith.
13. A structure as specified in claim 24 which also includes a coil of radiating pipes mounted on said frame and adjacent to said reservoir and included in the connection between said pump and reservoir.
14. In a locomotive tender, an underframe, superstructure including a rigid rear end frame, locomotive equipment mounted on said end frame, and conduits extending between said equipment and the locomotive and enclosed in a housing provided in said superstructure.
15. In a locomotive tender, an underframe, superstructure carried thereon including an upright rear end frame, locomotive equipment mounted on said end frame, and conduit extending between said equipment and the locomotive and passing through a housing therefor provided in said underframe.
16. In a locomotive tender, an underframe cast in one piece including an upwardly disposed wall and a bottom web arranged to form the bottom of the tender tank, an upright frame mounted on said underframe, locomotive equipment carried on said frame, an upright wall on said bottom web spaced from the side wall of the underframe and a horizontal web connecting said upright wall and side wall to form a partition in the underframe for a housing for piping leading to and from said equipment.
17. A locomotive tender underframe including a transversely disposed bottom web which forms the bottom wall of the tender tank, there being conduits for piping integral with said web and along the sides of the underframe.
18. In a locomotive tender, an underframe part, a member projecting upwardly therefrom and separate from the tender tank, and a fluid reservoir supported on said member and spaced a substantial distance above said underframe.
19. A box-like superstructure member for mounting on a locomotive tender outside the tender tank and having an air reservoir extending transversely thereof.
20. A one-piece box-like frame arranged for mounting on a locomotive tender underframe outside the tender tank and including a fluid reservoir as an integral part thereof.

WILLIAM A. NEWMAN.
